UNITED STATES PATENT OFFICE.

WILLIAM H. ROACH, OF LINDSAY, CALIFORNIA.

CONVERTIBLE CAN-OPENER.

1,374,032.

Specification of Letters Patent. Patented Apr. 5, 1921.

Application filed May 24, 1919. Serial No. 299,533.

To all whom it may concern:

Be it known that I, WILLIAM H. ROACH, a citizen of the United States of America, residing at Lindsay, in the county of Tulare and State of California, have invented new and useful Improvements in Convertible Can-Openers, of which the following is a specification.

The object of the invention is to provide 10 a convertible tool consisting of a can opener, corkscrew, and bottle-cap remover, wherein efficiency in operation is combined with compactness of structure; and to this end the invention consists in a construction, combination and relation of parts hereinafter 15 fully described, it being understood that changes in form and proportion may be resorted to within the scope of the appended claim without departing from the principles 20 involved.

In the drawings:

Figure 1 is a side view of the tool indicating its position when in use as a can opener,

Fig. 2 is an edge view of the same,

Fig. 3 is a detail transverse section on the plane indicated by the line 3—3 of Fig. 1,

Fig. 4 is a detail view of the blade, and

Fig. 5 is a similar view of the rest.

The shank or handle 10 is preferably of 30 looped form and is extended to provide a hook-shaped head 11, the base 12 of which carries a blade 13 which intersects or extends across the throat of the hook in the plane of a rest 14 having a concaved and corrugated 35 face 15 for contact with the side surface of a can, such as indicated in dotted lines at 16 in Fig. 1 in the operation of removing the can top. The blade is preferably provided with a beveled cutting edge, the bevel being

40 on the underside or away from the plane of the hook-shaped head 11, so that in the removal of the can head the beveled surface of the cutting edge serves to turn the edge of the wall of the can outward and downward to leave an unobstructed inner surface of the can wall and thus afford no obstruction at the edge to interfere with the removal of the contents of the can.

Pivotal mounted as at 17 upon the shank 50 or handle is a corkscrew bit 18 adapted to be folded entirely within the plane of the handle to occupy a position between the side surfaces thereof so as not to obstruct the

grip upon the tool when the can-opening element is in use, and at an intermediate point 55 the sides of the looped handle are connected by a bridge-piece or cross-bar 19 having a seat 20 of bayonet slot formation for the reception of the point of the corkscrew bit when folded, so as to further protect the 60 hand of the operator when the said bit is in its folded position and the can opener is in use. This bridge-piece or brace is extended terminally to form ears 21 which combine to 65 form a bottle-cap remover for use in connection with the ordinary crimped caps. The portion of the shank or handle beyond the cap-engaging jaws or ears 21 serves as a suitable rest or fulcrum upon the bottle cap in removing the latter from a bottle. 70

From the above description it will be seen that whereas the can-opener blade is protected by the hook-shaped head when the corkscrew or bottle decapping elements are 75 employed, the looped form of the shank or handle serves as a housing for the corkscrew and decapping jaws 21 when the can-opener element is employed. The reduction of the blade of the can opener to a point provides for the ready engagement thereof with the 80 side wall of a can, and the insertion of the blade to an extent sufficient to bring the bearing element 14 into engagement with the side of the can leaves the bearing element a fulcrum for the movement of the 85 tool in detaching the can top. The leverage in the use of the can-opening feature may be modified by the extent of introduction of the blade and hence the angular location of the length of the tool with reference to the 90 diameter of the can upon which the operation is being performed.

What is claimed is:—

A tool of the class described having a shank or handle and a hook-shaped head, a 95 bearing element depending from the extremity of the head and provided with a corrugated concave bearing surface for contact with a can wall, and a longitudinal tapering blade intersecting the throat of said head in the plane of the said bearing element, the hook overhanging and engaging the top of the can to act as a guide for the blade during the cutting operation of the latter.

In testimony whereof I affix my signature. 105
WILLIAM H. ROACH.
